Primary Examiner — Jeffrey D Asch*Assistant Examiner* — Carissa C Fitts(74) *Attorney, Agent, or Firm* — Suzanne Kikel(57) **CLAIM**

The ornamental design for a light up wallet, as shown and described.

DESCRIPTION

FIG. 1 is a perspective view of the inside of a light up wallet in a fully open position, showing my new design;

FIG. 2 is a perspective view of the inside of the light up wallet with the flap in a downward position;

FIG. 3 is a rear elevational view of the light up wallet of FIG. 1;

FIG. 4 is a front elevational view thereof;

FIG. 5 is a bottom plan view thereof;

FIG. 6 is a top plan view thereof;

FIG. 7 is a right side elevational side view thereof; and,

FIG. 8 is a left side elevational view thereof.

The broken lines shown in the drawings illustrate portions of the article that form no part of the claimed design.

1 Claim, 6 Drawing Sheets(56)
